HOUSE

Donald J. Scholz, Toledo, Ohio, assignor to Scholz Homes,
Inc., Toledo, Ohio, a corporation of Ohio

Filed Aug. 4, 1961, Ser. No. 66,194

Term of patent 14 years

(Cl. D13—1)

FIG. 1 is a front perspective view of a house embodying my new design;

FIG. 2 is a front elevational view of the house;

FIG. 3 is a rear elevational view in reduced scale;

FIG. 4 is an elevational view showing the left side of the house;

FIG. 5 is an elevational view of the house's right side; and

FIG. 6 is a top plan view in the scale of FIGS. 3 through 5.

For convenience of illustration, only parts of the brick side surfaces and the shingle roof have been shaded in the several views on the drawing. It is to be understood that these surfaces continue throughout the plain areas shown.

The dominating features of my design reside in the front of the house as shown in FIGURES 1 and 2.

I claim:

The ornamental design for a house, as shown and described.
